UNITED STATES PATENT OFFICE.

LOUIS PINNER, OF NEW YORK, N. Y.

VENDING-MACHINE.

No. 870,126.

Specification of Letters Patent.

Patented Nov. 5, 1907.

Application filed April 20, 1907. Serial No. 369,375.

To all whom it may concern:

Be it known that I, LOUIS PINNER, a citizen of the United States, residing at the city, county, and State of New York, have invented a new and useful Vending-5 Machine, of which the following is a specification.

My invention relates to improvements in vending machines in which the bottom article of a cross-stacked pile is released and ejected from the machine upon inserting a coin of a pre-determined value and operating 10 the machine.

Among the objects in view in constructing the machine were to provide means for feeding articles from a single, stationary cross stack; to provide mechanism to prevent articles from being jammed in the machine and 15 rendering it inoperative; to provide mechanism for coin locking which will operate only on the insertion of a proper coin; to so construct the machine that it will either deliver an article or return the coin; to provide mechanism whereby the coin cannot be recovered if the 20 machine vends an article. I attain these objects in the manner illustrated in the accompanying drawings of a preferred embodiment of my invention.

Figure 1 is a side, sectional view of my machine; Fig. 2 a detail view, partly in section, of the coin lock and 25 return device; Fig. 3 a like view of the automatic return device; Fig. 4 a like view of the delivering mechanism; Fig. 5 a front view of the delivering mechanism and coin device.

A suitable cabinet 1 is divided into upper and lower 30 compartments by a shelf 2. This shelf is apertured at 3 and carries the flanged, stationary guide ring 4. An apertured, ringed disk 5 is rotatably mounted in the guide ring 4, the aperture 6 corresponding in general size and shape with that of the article to be vended. 35 This disk is provided with the lugs 7, 7, 7, 7, projecting from its outer face. Upright guides 8, 8, 8, 8, are arranged in the upper compartment to receive and retain a cross-stacked pile of articles to be vended. The upper face of the rotatable disk is provided with a channel 40 9 into which the lower ends of the guides 8, 8, 8, 8, or extensions thereof, project. The lower compartment is provided with a delivery chute 11 through which the vended articles are conveyed to the vendee.

To effect the rotation of the disk, coin locked 45 mechanism is employed. This consists of the segment 12 mounted slidingly on the guide ring 4 and provided with an operating lever 13 projecting through a slot in the cabinet. A spring 14 is provided to return the lever

to its initial position after each operation of the machine.

50 The coin carrier 15 comprises a chambered piece open at top and bottom. As shown in Fig. 2 the chamber normally alines with a coin chute 16 and the coin, when in the chamber, bears on the flange on the guide ring, the upper part being in position to engage a lug on the rotatable disk to move same when the lever is pushed. When the lever has reached its extreme limit of movement the coin is over an aperture 17 in the shelf 2 and a cut out portion of the flange so that, being unsupported on the bottom, it falls into a money 60 box. The lever striking the end of the slot or other stop comes to a standstill while the momentum of the rotatable disk causes it to slightly overrun the coin block releasing the side pressure on the coin and jar- 65 ring it down into the money box if it has any tendency to stick. A second aperture 18 under the end of the chute 16 permits coins which miss the chamber to fall into the delivery chute for return to the vendee. 65

The operation of the machine is as follows:—A cross- 70 stacked pile of articles to be vended is placed in the upright guides, resting on the apertured plate or disk. A coin of predetermined value is placed in the coin chute and enters the chamber on the block. The lever is then pushed and the upper part of the coin en- 75 gages a lug on the rotatable disk moving it. As the ap- 75erture registers with the bottom article it is released and falls into the delivery chute from whence it can be removed by the vendee. The coin has meanwhile ridden along the flange on the guide ring until it has reached the cut out part over the money box opening 80 when it falls through the chamber and into the box. The spring on the lever segment thereupon returns the lever and coin chamber to initial position when the operation can be repeated on the insertion of a fresh coin. 85

If for any reason the coin chamber does not aline with the end of the coin chute, or the coin should miss the chamber it will fall through the return opening into the delivery chute and be returned to the vendee. As the bottoms of the guides extend into the channel in the 90 rotatable disk, and are therefore well below the bottom article, jamming of the machine by reason of articles being carried under the bottom of the guides is absolutely prevented.

This machine dispenses with the usual shaft carrying a disk provided with a plurality of apertures near 95

its edge and dispenses with a rotating stack, substituting a single, stationary stack and a rotatable disk having a single aperture. This construction is cheaper and more efficient and can be contained in a much 5 smaller cabinet.

I claim:-

1. In a vending machine the combination of a rotatable, apertured disk channeled on its upper face; guides thereover adapted to contain a cross stacked pile of articles to 10 be vended and extending into the channels in the disk; and means for rotating the disk to release the bottom article.

2. In a vending machine the combination of a guide ring; an apertured, rotatable disk therein having a channel in its upper face; guides thereover adapted to contain a 15 cross stacked pile of articles to be vended and extending into the channel in the disk; and means for rotating the disk to release the bottom article.

In testimony whereof I have hereunto subscribed my name in the presence of two attesting witnesses.

LOUIS PINNER.
